UNITED STATES PATENT OFFICE.

CALEB E. TOWER, OF SOUTH BEND, INDIANA, ASSIGNOR TO THE ECONOMIC PLOW COMPANY, OF SAME PLACE.

PLOW.

SPECIFICATION forming part of Letters Patent No. 354,752, dated December 21, 1886.

Application filed October 15, 1886. Serial No. 216,351. (No model.)

To all whom it may concern:

Be it known that I, CALEB E. TOWER, of South Bend, in the county of St. Joseph and State of Indiana, have invented a new and useful Improvement in Plows; and I do hereby declare that the following is a full, clear, and exact description of the same.

My invention relates to plows, and more particularly to a brace for the handles thereof, adapted to permit of the adjustment of the same in relation to the beam, whereby the same handles may be used either upon a right or left hand plow. Plow-handles are usually made right or left hand to fit right or left hand plows, and it is necessary for a dealer in farm implements to carry a large stock of handles in order to meet the demand for the two kinds of handles, for the one will not answer the purpose of the other.

It is the object of my invention to provide a brace for the plow-handles, which may also be used to adjust the handles in relation to the plow-beam, in order to adapt the same handles for use either in a right or left hand plow, thus reducing the stock of handles one-half, and mistakes are also prevented such as ordinarily occur by sending out a pair of right-hand handles with a left-hand plow, and vice versa.

30 Heretofore plow-handles have been provided with braces, and these braces have been adapted to receive and support the end of the beam, which was capable of adjustment upon the said braces; but this adjustment is not intended for the purpose of my invention, but simply to give the plow-beam a lateral adjustment when change was made in the number of horses used on the plow.

In the accompanying drawings, Figure 1 is 40 a plan view of a right-hand plow, showing my improved brace in position and the handles properly adjusted, while Fig. 2 is a like view of a left-hand plow. Fig. 3 is a detail sectional view through the brace. Fig. 4 is a detail showing a different form of fastening for the beam.

In the drawings, A represents the standard of the plow, which is of ordinary construction, and B represents the plow proper. The beam 50 is pivoted in any well-known manner, so as to be capable of lateral adjustment upon the

standard, for the purpose hereinafter described.

The handles are made alike, and are secured to the plow—one to the mold-board, and one 55 to the landside; or they may be secured to suitable braces, or both to the standard, as is sometimes done. The handles are supported, as is well known, in an inclined position, and a brace, C, is secured to the handles, as shown in 60 Figs. 1 and 2, with its upper surface in a horizontal plane, and in line with the lower surface of the plow-beam, which rests upon the same. The brace is formed upon its lower surface upon an angle, so as to fit snugly the incline of the handles. An ear, a, extends downwardly at the point shown on each end of the brace, bearing against the inner sides of the handles, and an ordinary bolt passes through an opening in the same and through the handles and holds them in position. Instead of the brace being secured in this particular manner, any other way will be equally as well.

From the plan views it will be seen that the brace is slotted at b c d, and the end of the 75 plow-beam rests upon the same, and is adapted to be held in these slots after the handles have been properly adjusted by means of an ordinary bolt passing through the slots to the under side of the brace, where it is suitably secured. It will be observed that the slots b and 80 d are formed upon different curves, and the purpose of this is to provide the proper adjustment for the handles in relation to the beam, according to the kind of plow to which 85 the handles are applied. If, for instance, the handles are applied to a right-hand plow, they are so placed that the end of the beam is held in the left-hand slot, b, which thus brings the handles in the proper relative position to the 90 beam and plow, and any suitable amount of adjustment of the beam may be made thereafter in this slot, according to the character of the soil and the number of horses used. If, however, a number of horses are used, and 95 the adjustment of the beam within the slot b is found insufficient, the adjustment may be increased by using the central slot, c, which is approximately straight.

When the handles are to be used upon a left-hand plow, they are so placed as to bring the beam in line with the right-hand slot, d, which

thus brings the handles in the proper position for a left-hand plow.

As shown in Fig. 4, I may dispense with the slots, and instead make the brace with a rib on its under surface curved in a corresponding manner to the slots above described, and a hooked bolt, *e*, may pass through the beam, having its shank suitably held by a nut, with its hooked end encircling the rib, as shown. The action in this case will be precisely the same.

I claim—

1. A brace for plow-handles, adapted to be connected with the plow-beam, formed with its points of connection at opposite ends upon different curves, whereby one set of handles may be used for either a right or left hand plow, substantially as described.
- 15 2. A brace for plow-handles, adapted for con-

nexion with the plow-beam, provided with 20 curved slots therein at opposite ends, said slots being formed upon different curves, whereby the handles may be used for a right or left hand plow, substantially as described.

3. A brace for plow-handles, having the end 25 slots, *b d*, formed upon different curves, the central intermediate slot, *c*, formed approximately straight, said brace being adapted for connection with the plow-beam, substantially as described.

In testimony whereof I have signed my name to this specification in the presence of two subscribing witnesses.

CALEB E. TOWER.

LEIGHTON PINE,
WILLIS A. BUGBEE.

Correction in Letters Patent No. 354,752.

It is hereby certified that the name of the assignee in Letters Patent No. 354,752, granted December 21, 1886, upon the application of Caleb E. Tower, of South Bend, Indiana, for an improvement in "Plows," was erroneously written and printed "The Economic Plow Company," whereas said name should have been written and printed "The Economist Plow Company"; and that the Letters Patent should be read with this correction therein that the same may conform to the record of the case in the Patent Office.

Signed, countersigned, and sealed this 28th day of December, A. D. 1886.

[SEAL.]

D. L. HAWKINS,
Acting Secretary of the Interior.
